(57) **CLAIM**

The ornamental design for a seal, as shown and described.

DESCRIPTION

FIG. 1 is a front view of a seal in accordance with an embodiment of the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof;

FIG. 8 is a cross sectional view taken along line 8-8 of FIG. 5;

FIG. 9 is an enlarged partial view of line 9-9 of FIG. 8; and, FIG. 10 is a referential view showing the state in use thereof. The dashed-dot-dashed lines shown in FIG. 8 and FIG. 9 are provided to define the enlargement regions depicted in FIGS. 8 and 9, respectively, and form no part of the claimed design.

The broken lines shown in FIG. 10 represent portions that form no part of the claimed design.

1 Claim, 4 Drawing Sheets
